COLLAR SUPPORTING AND IRONING DEVICE

Adolph A. Myers, Louisville, Ky.

Application July 15, 1935, Serial No. 31,399

4 Claims. (Cl. 223—52.6)

This invention relates to a new and novel collar supporting and ironing device which is particularly suited for use in shaping and finishing shirt collars.

5 At the present time the practice, in connection with the ironing of shirt collars, is to iron both sides of the neck band and flap, i. e. outer section of the collar, as one flat piece, manually crease the collar along the upper marginal edge of 10 the neck band and then button it to hold it in arcuate shape.

The principal object of this invention is to provide a simple and inexpensive collar iron which can be easily and quickly operated to finish a 15 manually creased collar and which is effective in one operation to iron both the crease and the neck band of the collar and restore its arcuate shape.

Another object is to provide a mechanism of this character which is suited for use equally with 20 attached and unattached collars.

25 The invention is illustrated in the accompanying drawing wherein:—

Figure 1 is a top plan view of a collar iron constructed in accordance with my invention, the iron being in ironing position;

Figure 2 is a front elevation thereof;

Figure 3 is a section along line 3—3 of Figure 1;

Figure 4 is a fragmentary side elevation showing the iron as it appears when raised out of the ironing position and indicating, in dotted lines, the end view of a collar on the band;

Figure 5 is a fragmentary rear end elevation of the iron;

Figure 6 is a bottom plan view of the ironing 35 face; and

Figure 7 is a section along line 7—7 of Figure 1.

In carrying out my invention, I provide a hollow vertical supporting standard 1 of suitable height and preferably of arcuate cross section. The lower 40 end of the standard is adapted to rest directly on the floor but it may, of course, be provided with supporting legs or otherwise arranged. The upper end of the standard carries a shoe 2 having an inner arcuate face to which the lower end of an arcuate band or collar support 3 is secured. An 45 attached or unattached collar, after being ironed flat and manually creased, is slipped or straddled over the band 3 with the neck band N and flap F respectively extending along inner and outer sides of the band 3. The interior of the hollow standard 1 provides a free or unobstructed space into which the shirt of an attached collar hangs, the standard, shoe and band all cooperating to define a front vertical opening through which a 50 shirt may be passed.

In order to iron the crease and neck band of the collar and also restore its shape, an iron 4 is provided with an ironing groove 5 arcuately shaped to fit over a collar positioned on the band 3 and to press against the creased and neck band portions 5 thereof. The iron 4 may be heated in any suitable manner but preferably is heated through the agency of an electrical heating unit suitably arranged in the interior of the iron. The neck band ironing face of the iron is provided by a member 10 6 which is slidably mounted on the body of the iron by means of bolts 6a passing upwardly through the member 6 and a recess in the body of the iron 4, this recess being wide enough to permit lateral movement relatively to the iron of the bolt 15 6a and its securing nut. This is yieldingly pressed toward the band by a spring 7 which provides the requisite ironing pressure. Naturally with the iron in position to iron a collar, it is only necessary to engage the handle 8 of the iron and move it 20 along the arcuate path defined by the band to effect the ironing operation. While the iron could be manually supported during such movement, it preferably is supported on a carriage 9 which is arranged for arcuate movement on the 25 shoe 2. To this end, the iron is pivotally secured to the carriage 9 for movement from its horizontal ironing position to a vertical inoperative position in which it is yieldingly or resiliently held by a 30 spring 10 connected between the iron and carriage.

The carriage 9, which may be of any suitable shape, is mounted to straddle a raised track 11 of the shoe 2. The opposite vertical faces of the track 11 are grooved to provide inner and outer trackways 12 into which the wheels 13 extend. These wheels are secured to the carriage and 35 movably support it on the tracks.

Having described my invention, I claim:

1. A collar supporting and ironing device comprising a collar supporting band providing a support over which a creased collar may be straddled, a trackway extending along the outer side of said band, and a collar iron supported on said trackway for movement along said band in ironing relation to a collar on said band. 40

2. A collar supporting and ironing device comprising a collar supporting band providing a support over which a creased collar may be straddled, a trackway extending along the outer side 50 of said band, a carriage mounted for movement along said trackway, and a collar iron pivotally supported on said carriage for movement from an inoperative position to an operative ironing position relatively to said band. 55

3. A collar supporting and ironing device comprising a collar supporting band providing a support over which a creased collar may be straddled, a trackway extending along the outer side of said band, a carriage mounted for movement along said trackway, a collar iron pivotally supported on said carriage for movement toward and away from said band, said iron having a neck band ironing part slidably secured to it for movement relatively toward and away from the inner surface of the band, and means for yieldingly urging said part toward said surface.
4. A collar supporting and ironing device com-

prising a band over which a creased collar may be straddled with the shirt side of the collar extending along the inner side of the band, and supporting means for said band, said band and supporting means being hollow through a depth 5 extending from the upper edge of the band sufficiently downward to provide a free unobstructed space in which the shirt of an attached collar may hang and having a side opening through which the shirt may be placed into or out of said 10 space.

ADOLPH A. MYERS.
